HAND CART FOR GARBAGE CANS AND SIMILAR ARTICLES

Sidney E. Gatewood, 25170 Waldorf, Roseville, Mich.

Filed Dec. 29, 1960, Ser. No. 63,381

Term of patent 14 years

(Cl. D14—3)

FIGURE 1 is a perspective view of a hand cart for garbage cans and similar articles, showing my new design;

FIGURE 2 is a side elevational view thereof; and

FIGURE 3 is a top plan view thereof.

The container shown in broken lines in FIG. 2 is included for illustrative purposes only.

The characteristic feature of my design for the hand cart disclosed resides in the curved base portion having the configuration shown.

I claim:

The ornamental design for a hand cart for garbage cans and similar articles, as shown and described.
